UNITED STATES PATENT OFFICE.

ARTHUR W. GRANT, OF SPRINGFIELD, OHIO.

DESIGN FOR A VEHICLE-WHEEL.

SPECIFICATION forming part of Design No. 24,555, dated August 13, 1895.

Application filed January 19, 1895. Serial No. 535,557. Term of patent 14 years.

To all whom it may concern:

Be it known that I, ARTHUR W. GRANT, a citizen of the United States, residing at Springfield, in the county of Clark and State of Ohio, have invented and produced a certain new and original Design for Rubber-Tired Vehicle-Wheels, of which the following is a specification.

In the accompanying drawings, Figure 1 is a side view of a wheel having a rim illustrating the design. Fig. 2 is a perspective view, on a larger scale, of a portion of said rim, which is also cut transversely to show the configuration. The rim consists of an inner portion *a* having the surface thereof facing the hub rounded in substantially the form of a half-circle, an outer portion *c* having its periphery rounded in substantially the form of a half-circle and its sides substantially flat and

inclined toward said periphery, and between said inner and outer portions a central portion *b* having one of its edges *b'* of substantially the same width as the inner portion *a*, but its other edge *b''* wider and projecting from the sides of the outer portion *c*. The faces of the central portion *b* are concaved between its edges *b'* and *b''*, and said edge *b''* is slightly rounded, as shown.

I claim—

The design for a vehicle wheel substantially as shown and described.

In testimony whereof I have hereunto set my hand this 31st day of December, A.D. 1894.

ARTHUR W. GRANT.
